UNITED STATES PATENT OFFICE.

CHARLES J. NASH, OF CHICAGO, ILLINOIS, ASSIGNOR TO UNIVERSAL DRAFT GEAR
ATTACHMENT CO., A CORPORATION OF ILLINOIS.

DRAFT ARM FOR RAILWAY CARS.

1,408,768.

Specification of Letters Patent.

Patented Mar. 7, 1922.

Application filed December 23, 1919. Serial No. 346,815.

To all whom it may concern:

Be it known that I, CHARLES J. NASH, a citizen of the United States, and resident of Chicago, county of Cook, and State of Illinois, have invented certain new and useful Improvements in Draft Arms for Railway Cars, of which the following is a specification and which are illustrated in the accompanying drawings, forming a part thereof.

10 In the construction of refrigerator cars it is the practice to apply below the car floor a layer of insulating material,—a fibrous material being used for this purpose and being held in place by a false flooring secured between the several sills. In the reconstruction of old cars having wooden center sills, by the application thereto of draft arms which extend up along the inner faces of these sills and arch over the car bolster, for the purpose of strengthening the underframing, difficulty has been encountered in providing for the introduction of such false flooring boards between the two center sills.

15 The object of the present invention is to provide a form of construction of draft arm of this type which will adapt it for use on refrigerator cars and provide for the introduction of the insulating material between the center sills. This object is secured

20 by providing the upstanding flange of such a draft arm with a suitable lateral flange or beading which will furnish a support for the false flooring, without seriously decreasing the strength of the arm.

25 An embodiment of the invention is herein-after described, and is shown in the accompanying drawings, in which—

Fig. 1 is a detail longitudinal central section of the underframing of a car;

30 Fig. 2 is a detail plan view of the central portion of the underframing;

Fig. 3 is a view similar to Fig. 1, showing a modified form of construction; and

35 Figs. 4 and 5 are detail sections on the lines 4—4 and 5—5, respectively, of Fig. 3.

The improved draft arm has the usual body portion 10 located below the center sill 11, and being provided with draft and buffering shoulders 12, 13, and, in the embodiment disclosed, extending backwardly to and abutting against the front face of the bolster 14. The draft arm is further provided with an outstanding flange, indicated at 15, at the upper margin of the body portion 10, and

underlying and being bolted to the center 55 sill, and with an upstanding flange 16 which lies along and bears against the inner face of the sill, this latter flange arching over the bolster, as indicated at 17.

An instanding bead or flange 18 is formed 60 on the flange 16, bounding the upper margin of the latter from its forward end and continuing backwardly across the deeper portion 17 of this flange which arches over the bolster, and bounding the rearward portion 65 of the flange 18 back of this widened section. A similar instanding bead or flange 19 bounds the upper margin of the widened portion 17 of the upstanding flange, the end of this bead, however, being spaced apart 70 from the bead or flange 18 a sufficient distance to permit the insertion of sub-floor boards 20 which rest upon the horizontal beads or flanges 18 of the two draft arms used in the car, which boards, together with 75 the flooring 21 of the car, form a pocket within which is packed the insulating material 22.

In assembling the parts the two draft arms having been secured to the sills, the 80 sub-floor boards 20 may be inserted from the rearward end thereof and shoved forwardly along the flange 18, the insulating material being inserted between the flooring and these boards as they are applied. In the modification illustrated in Fig. 3, the portion of 85 the bead or flange 18 intermediate of the ends of the widened portion 17 of the upstanding flange of the draft arm is shown as being interrupted, taking the form of a plurality of lugs 23 which, while forming an adequate support for the sub-floor boards 20, permit their more convenient insertion.

If desired the draft arm may be provided with a second instanding bead 24 at the base 95 of the upstanding flange 16, and upon which may be mounted a second sub-flooring 25 to support a lower layer of insulating material.

Back of the draft arm the flooring for carrying the insulating material may be supported upon strips 26, 27, nailed to the inner face of the sill, this feature, however, not forming a part of the claimed invention.

I claim is my invention—

1. In combination, a pair of draft arms, 105 each having an upstanding flange for bearing against the inner face of a center sill, the adjacent faces of such flanges being pro-

vided with longitudinal beads for supporting a sub-floor for carrying insulating material.

2. In combination, a pair of draft arms each having an upstanding flange bearing against the inner face of a center sill, and arching over the car bolster, each flange being provided with a horizontal instanding

bead throughout its length for supporting a sub-floor for carrying insulating material 10 and each having a second instanding bead bounding the portion thereof which arches over the bolster, the ends of the last-named beads being spaced apart from the first-named beads.

CHARLES J. NASH.
